(57) **CLAIM**

The ornamental design for a dosage packaging for washing agents, as shown and described.

DESCRIPTION

FIG. 1 is a top, front perspective view of a dosage packaging for washing agents according to our new design;

FIG. 2 is a top plan view thereof;

FIG. 3 is a bottom plan view thereof;

FIG. 4 is a front view thereof;

FIG. 5 is a back view thereof;

(Continued)

FIG. 6 is a right-side view thereof; and,
FIG. 7 is a left-side view thereof.

The broken lines illustrate portions of the article that form no part of the claim. The dot-dash lines represent the boundaries of the claim and form no part thereof.

1 Claim, 5 Drawing Sheets
